UNITED STATES PATENT OFFICE.

FRANK RIES, OF TIFFIN, OHIO, ASSIGNOR OF ONE-FOURTH TO LEE BUCKINGHAM AND ONE-FOURTH TO JOHN A. BAIN, OF TIFFIN, OHIO.

DUPLICATING APPARATUS.

No. 873,788.

Specification of Letters Patent.

Patented Dec. 17, 1907.

Application filed February 4, 1907. Serial No. 355,651.

To all whom it may concern:

Be it known that I, FRANK RIES, a citizen of the United States, residing at Tiffin, in the county of Seneca and State of Ohio, have 5 invented a new and useful Duplicating Apparatus, of which the following is a specification.

This invention relates to duplicating apparatus for use in preparing way-bills, etc.

10 The object of the invention is to provide a light, durable and effective means whereby entries upon a way-bill or other blank may at the same time be quickly and accurately reproduced upon one or more blanks such as 15 a delivery sheet and a stub.

A still further object is to provide a pad supporting board or base having duplicating mechanism attached thereto which will adjust itself automatically to pads of different 20 thicknesses.

Another object is to provide simple means for holding the carbon sheets of the apparatus in proper positions.

With these and other objects in view the 25 invention consists of certain novel features of construction and combinations of parts which will be hereinafter more fully described and pointed out in the claims.

In the accompanying drawings is shown the 30 preferred form of the invention.

In said drawings: Figure 1 is a plan view of the apparatus; Fig. 2 is a section on line $x-x$, Fig. 1; Fig. 3 is a transverse section through the apparatus; Fig. 4 is a detail view 35 of one end of the frame and showing the carbon holding clip; and Fig. 5 is a perspective view of the device, the frame being shown raised.

Referring to the figures by characters of 40 reference, 1 is the base of the apparatus on which is mounted a pad 2 divided by scoring into three parts, to wit, a way-bill 3, a delivery sheet 4, and a stub 5. The stub and way-bill are printed upon their upper faces, 45 whereas the delivery sheet is printed upon its lower face. It is therefore apparent that when the delivery sheet 4 is folded back over the stub its printed face will be uppermost.

A leaf 6 is hinged to one side of the base 1 50 adjacent one end thereof and secured upon this leaf and extending throughout the width thereof is a guide plate 7 spaced from the leaf a sufficient distance to permit the passage of a strip of carbon. This leaf is formed 55 with a sleeve 8 at its outer edge through

which extends a pivot rod 9 having a threaded end adapted to be engaged by a winged nut 10. Pivotedly mounted on the end portions of this rod are links 11 connected at one end by a cylindrical cross bar 12 of wood or 60 other light material. Loosely mounted on this bar is a metal sleeve 13 formed at one end of a frame 14. This frame is in the form of an L-shaped arm 15 extending throughout the width of the pad 2 and having its side 65 extension 16 of the same length as the respective sections of each sheet of the pad. This extension 16 has its free end connected to sleeve 13 by means of a wire 17 and another wire 18 is strung across the pad 2 along 70 the score line between the delivery sheet and the stub.

Ears 19 extend from sleeve 13 and constitute bearings for a small guide roller 20 preferably covered with rubber. Arms 21 are 75 soldered or otherwise secured to sleeve 13 and extend tangentially therefrom to constitute bearings for a spool 22 on which is wound a strip of carbon paper 23. This strip passes between sleeve 13 and roller 20 80 and thence longitudinally of the frame 14. The end of the strip is folded over the extension 16 of said frame as shown particularly in Fig. 4 and is held thereon by a clip 24 in the form of a resilient channeled strip which 85 is pivoted to the extension 16 as shown at 25 and is adapted to embrace the folded portion of the carbon strip and clamp it upon the extension 16, as shown in Fig. 4.

A plate 26 extends beyond one edge of leaf 90 6 and has upstanding arms 27 between which is journaled a spool 28. This spool carries a strip of carbon 29 which is extended between the leaf 6 and guide plate 8 and rests upon the stub 5 of the top sheet of the pad. A 95 handle 30 is connected to the frame 14 so that by pushing laterally thereon said frame can be swung upward from the pad. During this movement either the bar 12 or the rod 9 will act as a fulcrum or the two can act simultaneously 100 as separate fulcrums.

In using the device herein described the frame 14 is swung into an upright position so that the spool 22 will rest upon the plate 7. The lower carbon strip 29 is then pulled 105 under the guide plate 7 and placed over the stub of the top sheet of the pad. The wire 18, as heretofore stated, rests upon the score line between the delivery sheet 4 and the stub 5. Said delivery sheet can therefore be 110

folded back over this wire and above the carbon strip 29. The frame 14 is then lowered so that the carbon strip 21 carried thereby will rest upon the delivery sheet after which 5 the way-bill 3 is folded over the wire 17 carried by frame 14 so as to assume a position above the upper carbon strip 21. The three 10 divisions of each sheet of the pad are so printed that certain spaces indicated thereon for the reception of data are disposed above each other when the sheet is folded in the manner described. It is therefore apparent that when entries are made upon the way-bill they will be duplicated by the carbon 15 strips upon the delivery sheet and the stub. After the entries have been made the frame 14 is raised and the sheet which has been marked is removed from the pad and torn along the score lines. If preferred, however, 20 the way-bill can be torn along the wire 17 before the frame 14 is raised after which the delivery bill can be torn along the wire 18. As the carbon becomes worn it can be easily 25 readjusted. The lower carbon is adjusted simply by pulling it from under the guide plate 8 and tearing off the used end thereof. The upper carbon 21 is re-arranged by first 30 swinging the clip 24 out of engagement with the end thereof and then pulling the strip longitudinally a desired distance after which it is re-secured by means of the clip and the end torn off along the edge of the clip.

It will be seen that by providing apparatus herein described two copies of any data 35 entered upon a way-bill can be quickly and accurately produced. By providing the link connections between the frame 14 and the leaf 6 said frame will adjust itself to a pad of any thickness so that the carbon sheets 40 will at all times rest smoothly upon the pad.

As the device is very compact and light it can be conveniently carried and is therefore rendered especially suitable for express and freight agents.

45 What is claimed is:

1. The combination with a base; of a leaf hinged thereto, a guide plate upon the leaf, and a duplicating strip carried by the leaf and extensible beneath the guide plate and 50 across the base.
2. The combination with a base; of a leaf hinged thereto, a guide plate secured to the leaf, a roller supported above said plate and upon the leaf, and a duplicating strip sup- 55 ported by the roller and extensible beneath the guide plate and across the base.

3. The combination with a base; of a leaf hinged thereto, a duplicating strip carried by the leaf and extensible across the base, a 60 guide for said strip and upon the leaf, a frame movably connected to the leaf, and a duplicating device carried by said frame.

4. The combination with a base; of a leaf hinged thereto, a duplicating strip carried by the leaf and extensible across the base, a 65 guide for said strip and upon the leaf, links pivotally connected to the leaf, a frame pivotally connected to the links, a duplicating strip carried by and extending longitudinally of the frame.

70 5. The combination with a base; of a leaf hinged thereto, a duplicating strip carried by the leaf and extensible across the base, a 75 guide for said strip and upon the leaf, a frame movably connected to the leaf, a duplicating device carried by said frame, and means upon the base and frame for facilitating the folding of a sheet thereon.

6. The combination with a base and means 80 extending thereacross for facilitating the folding of a sheet; of a frame pivotally connected to the base and disposed to be moved onto a folded sheet, and a duplicating strip carried by the frame, said frame constituting means upon which a sheet is designed to be 85 folded.

7. The combination with a base and means 90 extending thereacross for facilitating the folding of a sheet upon the base; of a frame constituting means upon which said sheet is 95 designed to be folded, a duplicating strip carried by the frame, and means connecting the base and frame whereby said frame may be held parallel with and at different distances from the base.

95 8. The combination with a base; of a leaf hinged to one side of the base, a frame pivotally connected to the leaf and disposed to rest parallel with the base and at different distances therefrom, a duplicating strip carried by the leaf and extensible over the frame, and separate means upon the frame and base for facilitating the folding of a sheet under and over the frame.

100 In testimony that I claim the foregoing as my own, I have hereto affixed my signature in the presence of two witnesses.

FRANK RIES.
